INSTRUMENT FOR DRAWING CIRCULAR
AND CURVILINEAR LINES

Gustave A. Haederer, Philadelphia, Pa.

Application June 30, 1944, Serial No. 542,939

12 Claims. (Cl. 33—177)

1

This invention relates generally to drafting instruments and more particularly to a changeable curve adapted for use by draftsmen for drawing such regular or irregular curves as the occasion may require and for readily making available the data by means of which any such curve may be readily reproduced.

One of the principal objects of the invention is to provide in such an instrument a means whereby curves which are arcs of true circles, as well as irregular curves variable in extremely fine degree, may be obtained.

Another object of the invention is the provision in such an instrument of an inherently flexible portion pivotally connected with the main body portion of the instrument in spaced relation with respect thereto, in combination with a plurality of means operative to variably adjust the position and relation of said flexible portion with respect to said body portion to thereby vary, as desired, the curvature of the drawing edge of said flexible portion.

Further objects and advantages will be apparent from the following detailed description in which like reference characters refer to like parts in the drawings, in which:

Figure 1 is a plan view of one face of the instrument constructed in accordance with and embodying the present invention and in which the guide rule or beam portion of the instrument is shown in its straight line position;

Figure 2 is a top plan view of the main body member portion of the instrument;

Figure 3 is a plan view of the opposite face of the instrument showing the beam-setting dial graduated in divisions which represent the radii of circles;

Figure 4 is a sectional view of the instrument taken on line 4—4 of Figure 1;

Figure 5 is a sectional view of the instrument taken on line 5—5 of Figure 1;

Figure 6 is a sectional view of the instrument taken on line 6—6 of Figure 1;

Figure 7 is a fragmentary view, partially in section taken on the line 7—7 of Figure 4 showing the instrument set for one position of the beam-setting dial;

Figure 8 is a similar view showing the instrument set for another position of the beam-setting dial;

Figure 9 is a fragmentary view of the central portion of a modified form of construction of the instrument; and

Figure 10 is a vertical sectional view of the said modified construction of the instrument.

Referring more particularly to Figure 1 of the drawings, it will be observed that the drawing instrument essentially comprises a main body portion 10; a relatively flexible beam portion 11 positioned alongside the body portion and spaced

therefrom; a pair of curved arm portions 12—12 fastened to and interposed between each of the corresponding opposite ends of the body 10 and supporting the beam 11; and a plurality of flexing means 5 interposed between the body 10 and the beam 11 for flexing the latter into various curved positions, the said means comprising a centrally disposed rotary flexing means 13 and a pair of slidable flexing members 14 and 15.

The main body portion 10

Referring to Figure 2, the main body portion 10 which may be formed of any suitable relatively non-flexible material is preferably in the form of an elongated flat ruler-like member having parallel opposed faces with certain undercut areas therein and having one straight side, the latter being formed into the ruling or drawing bevel edge 16, provided, on each face thereof, with 20 a suitably graduated scale E.

At the center of the body 10 are the circular under-cut areas 17, in each face of the body, and also at the body center is the open end slot 18 formed in the body 10 and located centrally of the undercuts 17, all for a purpose to be herein-after described. It will be noted that the circles forming the outline of the circular undercuts 17 are not located wholly within the plane of the body 10, but that a portion of the same, which is less than 180 degrees, is cut off by the upper edge 25 of the body. The center flexing means 13 is located within the slot 18 and the undercuts 17.

The edge of the body 10 opposite from the straight beveled edge 16, on both sides of the center, is formed to provide a pair of oppositely inclined slightly curved edges 19 and 20, the main body 10 being thus widest at the center and tapering, along the edges 19 and 20, to the narrower opposite end extremities thereof. Each face of 35 the body, in the area of the edges 19 and 20, is undercut at 21 and 22, and is provided with suitably graduated scales marked A and B and designated in the drawings by the reference numerals 30 23 and 24. The side flexing means 14 and 15 are disposed for slidable movement along these undercut edges 19 and 20, as will presently appear.

Formed in the body 10 adjacent each end thereof are the holes 23—23 and 24—24, these being provided for the purpose of securing the 45 corresponding ends of each pair of the curved arm portions 12—12 to the body 10. Each face of the body, in the area of the holes 23—23 and 24—24 is undercut as at 24a. It will be noted that there are several parts which are located on or 50 fastened to the main body 10, namely the center flexing means 13, the side flexing means 14 and 15, and the arms 12—12. It will also be noted that each face of the body 10 has been undercut at those specific places where the several designated parts are to be located in order that, when

3

the said parts are operatively mounted in position upon the main body portion of the instrument, the opposite faces of the latter will present smooth flat surfaces; such as is desirable in drawing instruments.

The beam portion 11

It will be noted that the beam 11, extending alongside of and almost the full length of the body 10, may be formed of Celluloid, xylonite, amber, wood, metal or any plastic composition having the requisite degree of flexibility for the functions to be described. As appears in Figure 1, this beam 11, which has parallel faces, is long, flat and narrow, being wider at the center and tapering gradually in width to each end thereof. In the form shown in Figure 1, the lower or inner edge of the beam 11 is of arcuate, i. e. circular, form, while its outer longitudinal edge 26 is straight when the beam is in its unflexed condition. The beam 11, which is somewhat thinner than the body 10, is so disposed operatively with respect to the body 10 that in all of its various positions of curvature it lies substantially in the plane of its supporting body 10 (see Figure 4).

The beam 11 is supported in the position shown in Figure 1, lengthwise of the body 10, by means of the arms 12-12 extending upwardly from the body 10 and curving toward each other. Each end 27 of the beam 11 is provided with a hole 28 in which is received a bushing 28a which bears upon a bearing pin 29, preferably drilled and tapped at each end to receive the screws 30-30, which pass through countersunk holes in the ends of the curved arms 12-12, thus pivotally securing the ends of the beam to the upper ends of the curved arms. The beam 11 is also provided with a hole 31 through the center thereof extending at right angles to the plane thereof and with a transversely extending bore 32, this bore extending through a part of the beam 11 from the edge 25 of the beam inwardly to the hole 31.

As shown in Figure 1, the outer edge 26 of the beam 11, i. e., the edge most remote from the body 10, is straight whereas the inner edge 25 of the beam is of arcuate curvature coinciding with the arc of a circle. It is within the scope of this invention to have the shapes of the edges of the beam changed with relation to each other without departing from the spirit of the invention and without detracting from the accurate operation of the drawing instrument. Specifically, the edge shapes may be reversed with the edge 26 of arcuate, i. e., circular curvature, and the edge 25 straight, or both edges 25 and 26 may be arcuately curved. The theory of the invention supporting the statement that the accurate operation of the drawing instrument will not be effected by the above changes in the shape of the edges of the beam, will be set forth after the instrument itself has been fully described.

The arms 12—12

The pair of arms 12—12, which are secured to each opposite end of the beam 11, are also secured to each end of the body 10 by means of the screws 33—33 which freely pass through a hole in one of the arms 12 and threadedly engage a tapped hole in the other of the arms 12. Interposed between the base portions 34 of each pair of the arms 12—12 is the undercut end portion 24 of the body 10. Each of the lower holes 24—24 provided in the undercut end portion of the main body member 10 is fitted with a spacer 35 through which extends the securing screw

33. Interposed between the spacer 35 and the hole 24 in which it is fitted is a bearing sleeve 35^a about which the lower ends of the arms 12-12 are adapted to pivot. The upper holes 23-23 are also fitted with spacers 36 through which the screws 33 pass. However, clearance is provided between each spacer 36 and its corresponding hole 23, to thereby permit the arms 12-12 and the beam 11 to pivot about the lower pin 35 within the limits afforded by the clearance between the spacer 36 and its accommodating hole 23.

The central rotary flexing means 13

15 Referring to Figures 1 and 4, the center flexing means 13 includes an inverted U-shaped member 37 slidably fitted into the open-end slot 18 in the body 10. Provided in the base portion of the U-shaped member 37 is a hole 37a through which freely passes the threaded shank 38 of an inverted T-shaped member, the horizontal portion of which is in the form of a short tubular element 38a. The said threaded shank, after passing through the hole in the base of the U-shaped member 37, continues through the bore 32 in the beam 11, and is threaded into a cylindrically shaped member 39 which is closely fitted into the hole 31 in the beam 11. A fastening nut 40 is threaded on the member 38 and, when tightened, holds these parts in place as shown.

30   ... holds these parts in place.
1   Passing through the short tubular element
e   38, forming the head of the member 38 is the
e   freely rotatable pin 41 upon the oppositely pro-
f   jecting ends of which are secured similar rollers
s   42-42. These rollers 42-42 respectively ride
35   in the spirally-shaped cam path slots 43-43 re-
o   spectively formed in circular cam members
f   44-44, the latter being respectively fitted in the
s   circular undercut portions 17 formed in each op-
e   posite face of the body 10. The cam members
40   44-44 move together, being secured to each other
e   by an eccentrically positioned hub member 45,
y   which is provided with a hexagonal shaped recess
45   or socket 46 extending therethrough. The pur-
   pose of the socket 46 is to permit the insertion
   of a specially shaped key therein (not shown).

of a hexagonally-shaped key therein (not shown) by means of which the cam members 44-44 may be readily turned to any desired position. Secured to the outer faces of the cam members

50. 44—44 are the two graduated dial plates 47 and 47^a by means of which the required positional adjustment turning of the cam members 44—44 may be visually determined and indicated. The dial

be visually determined and indicated. The dial 47 is graduated, as seen in Figure 1, into uniform divisions and subdivisions to form a suitable scale C. The dial 47^a is also graduated to provide

scale C. The dial A is also graduated on a scale D, as seen in Figure 3, but its divisions and sub-divisions are non-uniform, the graduations being suitably calibrated to represent the radii of the circles from 1 to 100 ft. in the model.

60 of circles from 36 inches to 100 ft., in the model of the drawing instrument as shown. It will be noted that the flexing means is relatively fixed in place at the center of the body 10, except for its own rotary action, due to the spirally 65 grooved cam members 44-44 which are locked in the undercut circular portions 17, since the latter is greater than 180 degrees and prevents any lateral displacement of these cam members.

In the operation of the flexing means 13, when the cams 44-44 are rotated clockwise, viewing Figure 1, the cam paths 43-43, acting on the rollers 42-42, cause the member 38 to be moved outwardly from the body 10 toward the beam 11 and force the latter away from the body 10. This causes the beam to flex and to pivot about the

bearings 35a—35a and thus impart a curvilinear outline to the drawing edge 26 of the beam. Movement of the cams 44—44 in the opposite counterclockwise direction will positively draw the beam 11 back toward the body 10, the movement of the beam 11 being positive in each direction due to the double cam faces of the spiral paths 43—43 acting on the rollers 42—42. An index 48 is provided on one face of the body 10 for cooperation with the scale on the dial 45, while an index 49 is provided on the opposite face of the body 10 for cooperation with the scale on the dial 47.

The slideable flexing members 14 and 15

Referring particularly to Figures 1 and 5, the side flexing means 14 and 15, which are identical, are slideably disposed respectively between the inner edge 25 of the beam 11 and each of the edges 19 and 20 of the main body 10. Each of these slideable flexing members 14 and 15 comprises a pair of discs 50 and 50a (see Figure 5) held together by a central hub in the form of a tubular rivet 51 to provide each member with flanges 52 and 53 forming an annular channel or groove adapted to accommodate, on one side, the inner edge of the beam 11 and, on the other side, the proximate edge of the body 10. On the inner side of each sliding member 14 and 15, the channel is flattened, as at 54, to provide a substantial seat for the straight edge portion of the body 10 which is accommodated therein and along which the member is slideable, this flattened portion 54 serving additionally to prevent rotation or rocking of the member about its central axis. Suitable shaped springs 55 are interposed between the flattened edge portions 54 of the channels and each edge 19 and 20 of the body member 10 to maintain the flexing members 14 and 15 in secure frictional engagement with the beam 11 and to prevent any accidental movement with respect thereto. An open index 56 is provided in the flange of each of the slideable flexing members 14 and 15 to cooperate, respectively, with the scales 23 and 24. The size and shape of the flexing members 14 and 15 is such that, with the index 56 set at zero, the beam 11 is not flexed thereby. However, any movement of the members 14 and 15 along their scales respectively 23 and 24 causes a force to be exerted tending to flex the beam 11 outward from the body 10.

Operation

In the use of the drawing instrument above described for the purpose of drawing curves, other than arcs of circles, the beam 11 is adjusted to the desired regular or irregular shaped curve by means of the center flexing means 13 and/or one or both of the slideable side flexing members 14 and 15. This is effected by turning the dial 47 clockwise (see Figure 1), and by moving the side flexing members 14 and 15 toward each other, from their zero positions, until the beam 11 is curved to the desired position. One side flexing member may be moved further than the other in forming an irregular shaped curve and the side flexing members may be used, in certain instances, without the center flexing means. The center flexing means positively controls the movement of the beam 11 in each direction toward and away from the body 10 and so may be employed to maintain the center of the beam 11 fixed in position while the side flexing members 14 and 15 are employed to outwardly flex the ends of the beam 11. Thus, a

compound curve of almost any desired irregular shape may be obtained. It will be noted that the scales A and B in conjunction with their respective indices 56—56 on the slideable elements 14 and 15 and the scale C of the dial 47 in conjunction with its fixed index 48 may be used to accurately position the side flexing members 14 and 15 and the center flexing means 13 at any predetermined positions, or they may be used to accurately record their positions. The length of any given curve and/or the position of the same with respect to the drawing instrument, with the flexing means in given positions, may be determined by means of the scale E on the bevel edge 16. Thus, by means of scale data recorded from the scales A, B, C and E of the drawing instrument, any curve may be accurately and quickly reproduced at any time and may be described for reproduction by one or more duplicate drawing instruments at any distance from the instrument making the original curve.

For the purpose of drawing arcs of true circles, the beam 11 is flexed by the center flexing means 13 only, with the side flexing members 14 and 15 set and maintained at zero on the scales A and B. To do this, the instrument is reversed in position so that the dial 47a and consequently the scale D is uppermost. This dial is rotated counterclockwise (see Figure 3) to cause the beam 11 to be flexed in the manner already described. It will be noted that the first large division on the scale D is marked 100 ft., indicating that when this division is opposite the index 49 that then the beam 11 is flexed to a curve which is an arc 35 of a circle having a radius of 100 ft. When the index is set at either of the two smaller divisions preceding the 100 ft. division, the beam 11 will be flexed correspondingly to produce the true arcs 30 of circles of 200 and 300 foot radii. At the position of the dial 47a shown in Figure 3, and with the parts relatively arranged as shown in Figure 7, the beam 11 is a straight line which is the arc of a circle having an infinite radius. When the dial 47a has been turned 360 degrees, it will 35 be noted that the beam 11 will then have been flexed to a curve which is an arc of a circle having a radius of 36 inches. Accordingly, for the model of the drawing instrument shown, the arcs will vary from those of circles of 36 inch 40 radius to those of circles of 300 ft. It will be understood, of course, that different models may be provided suitably calibrated to produce arcs of circles of a radius range other than that shown in the drawings and described herein, without departing from the general principles and constructional details of the instrument of the 45 present invention.

The outline of the beam 11 has previously been described as having the straight edge 26 and the curved edge 25; it has also been set forth that the shapes of these two edges may be reversed or that the two edges may each be of curved shape without departing from the spirit of the invention or from the efficiency of the instrument in flexing the beam 11 into arcs of true circles. The force 50 flexing the beam 11 is exerted by the flexing means 13 at the center of the beam 11 and this force acts to bend the beam which, at the same time, tends to pivot about the bearings 35. The structural resistance within the beam, to the bending action of the flexing force imparted by the flexing means 13, due to the taper thereof 55 from the center to the ends, decreases gradually from a maximum at the center of the beam to a minimum at the ends thereof and this corre-

sponds exactly with the decrease in the torque action on the beam from the center to the ends of the beam; the torque action at the center of the beam tending to turn the same about the bearing 35 being the maximum and the torque action at the ends of the beam being a minimum. Accordingly, the curved tapered construction of the end pivoted beam 11 provides curves which are arcs of true circles. These results have been substantiated by experiments by comparing the curves produced by the drawing instrument with the arcs of circles known to be accurate. In all of these instances the curves produced by the drawing instrument have matched perfectly with arcs of the true circles. The scale D, in fact, has been calibrated by registering the curve of the beam 11 with arcs of true circles whose radii are known. Consequently, the instrument of the present invention is capable of employment to measure and determine the radii of arcs of true circles, it being merely necessary in order to accomplish this purpose to so adjust the dial 47^a that the outer edge of the beam 11 defines an arc which is coincident with that of the arc the radius of which is to be determined. The graduation on the dial 47^a which is then in registry with the index 49 provides an accurate indication of the radius of the arc being measured. Of course, in this use of the instrument, the sliding elements 14 and 15 will be set at their zero points along the scales A and B; one or the other or both of these elements being shifted out of their zero positions only when the instrument is employed to delineate curves of regular or irregular form which are not arcs of true circles.

Figures 9 and 10 show a modified construction of the instrument of the present invention, the purpose of this modification being to provide an arrangement which dispenses with the need of employing a separate or independent key for effecting rotation of either of the center dials 47 and 47^a. In general, this modified construction is in all respects similar to that hereinbefore described. However, instead of the flat dial plates 41 and 47^a which are respectively secured to the outer faces of the cam members 44-44 as in the form of construction previously described and shown in Figures 1 to 8, inclusive, in the modified construction of Figures 9 and 10, these dial plates, respectively designated by the reference numerals 60 and 61, are each centrally depressed, as at 62, to provide a circular seat or depression for receiving the knob 63 of an operating key for rotating the cam members. This key includes a shank 64 which is non-rotatably, but slidably, fitted within the bore 65 of the central hub member 66 to which the cam members 44-44 are secured. Identical operating knobs 63-63 are secured to opposite ends of the shaft 64 of the operating key, the arrangement being such that the key is adapted to be shifted laterally to one side or the other of the main body of the instrument so that one or the other of the operating knobs 63-63 is seated within its corresponding depression 62 provided in the adjoining dial plate and to insure that the outer surface of the knob 63 is perfectly flush with the surface of the dial plate in the depression of which the operating knob is seated.

Assuming, for example, that it is desired to employ the instrument with the dial face 60 uppermost, the operating key is shifted to the left as shown in Figure 10, in which position the operating knob 63 for rotating the dial 60 is outwardly spaced from the uppermost face of the instru-

ment sufficiently to permit the draftsman to conveniently grasp the same for operation thereof. At the same time, the opposite knob 63 lies within the depression of the dial face 61 and so insures a flush surface for the lower face of the instrument. When it is desired to employ the dial face 61, the operating key is shifted to the right and into the dotted line position shown in Figure 10, in which case the operating knob immediately associated with the dial face 60 is flush therewith. In all other respects, the instrument of Figures 9 and 10 is similar, both in construction and in operation, to that previously described.

It will be understood that the drawing instrument as hereinbefore described is susceptible of various other changes and modifications which may be made from time to time without departing from the general principles or real spirit of the present invention, and accordingly, it is intended to claim the same broadly, as well as specifically, as indicated by the appended claims.

What is claimed as new and useful is:

11. A drafting instrument comprising a main body member, pivotally movable arms secured to each end of said body member, a flexible beam secured at its ends to said movable arms, the adjacent edges of said body member and of said beam being spaced from each other, and slideable means disposed in said space and interengaging said adjacent edges for varying the position of said beam with respect to said body member, the said arms being automatically shiftable relatively to the body member to compensate for variations in the position of said beam.

12. A drafting instrument comprising a main body member, a flexible beam pivotally secured at its ends to said body member, the adjacent edges of said body member and of said beam being spaced from each other, rotary means at the center of said body and other means disposed in said space on each side of said rotary means and slideable longitudinally with respect to said body and said beam, all of said means being operative to vary the position of said beam with respect to said body member.

13. An instrument for use in the delineation and measurement of curvilinear lines comprising a relatively rigid main body member, a flexible beam pivotally secured at its opposite ends to corresponding ends of said main body member, rotary means interposed between said body member and said beam for positionally adjusting the latter into varying positions of curvature, said rotary means being provided with oppositely disposed calibrated dials, the surfaces of which are respectively disposed substantially flush with opposite faces of said main body member, and fixed indices on said body member for use in conjunction with the graduations of said calibrated dials.

14. An instrument as defined in claim 3 wherein said oppositely disposed dials are each graduated for selective use in the delineation or measurement of curvilinear lines of different character.

15. An instrument as defined in claim 3 wherein said oppositely disposed dials are each graduated for selective use in the delineation or measurement of curvilinear lines of different character, at least one of the dials being calibrated for use in the delineation or measurement of curves which are coincident with the arcs of circles.

16. In an instrument as defined in claim 3 wherein means are provided for effecting rotary adjustment of said rotary means.

7. In an instrument as defined in claim 3 wherein said rotary means includes an operating means therefor in the form of an axially shiftable shaft non-rotatably keyed to said rotary means, said shaft being provided at its opposite ends with operating knobs and said oppositely disposed dials being provided with depressions therein for respectively accommodating said knobs in flush relation with respect to the outer surfaces of said main body member when said operating means is axially shifted to its full extent in one direction or the other.

8. In an instrument adapted to be disposed flatwise for use in delineating or measuring lines and having a pair of rotatable scales respectively disposed upon opposite sides thereof with their outer surfaces substantially flush with the corresponding outer surfaces of said instrument, means for effecting selective rotation of said rotatable scales including an axially shiftable shaft non-rotatably keyed to said rotatable scales, said shaft being provided at its opposite ends with operating knobs and said oppositely disposed scales being provided with depressions therein for respectively accommodating said knobs in flushed relation with respect to said outer surfaces of the instrument when said operating means is axially shifted to its full extent in one direction or the other.

9. In an instrument having opposite flat surfaces selectively adapted to be disposed flatwise against a supporting surface for use in the delineation or measurement of lines, a relatively movable scale and index operatively provided in said instrument, and means for effecting relative movement between said scale and index including an operating key operatively associated with the movable element of said scale and index and shiftable laterally of the plane of said instrument, said operating key being provided at opposite ends thereof with operating knobs respectively adapted to be accommodated within depressions therefor formed in the opposite outer surfaces of the instrument, the arrangement being such that as said operating means is laterally shifted to its full extent in one direction or the other, the said operating knobs thereof are selectively disposed in flush relation with respect to their immediately associated outer surfaces of the instrument.

10. An instrument for use in the delineation and measurement of circular lines comprising a relatively rigid main body member, a flexible beam having its opposite ends movably secured to corresponding ends of said main body member, said flexible beam being provided with a free drawing edge and being characterized in that at least one edge of the beam throughout its full length extending freely between the movably secured ends thereof, when in unflexed state, is of a curvature capable of causing said free drawing edge to assume varying degrees of circular curvature when the beam is flexed upon the application of a force applied to the center thereof, and beam deflecting means interposed between said main body member and the midpoint of said beam operative to apply a deflecting force to the beam for varying the curvature of the latter, said means being so disposed and operative relatively to the secured ends of the beam as to be capable of imparting to the free drawing edge thereof a curvature coincident with the arc of a circle, and additional means interposed between said main body member and said beam for varying the curvature of the latter in the regions thereof respectively extending between its pivoted ends and said first-mentioned means.

11. An instrument for use in the delineation and measurement of circular lines comprising a relatively rigid main body member, a flexible beam having its opposite ends movably secured to corresponding ends of said main body member, said flexible beam being provided with a free drawing edge and being characterized in that at least one edge of the beam throughout its full length extending freely between the movably secured ends thereof, when in unflexed state, is of a curvature capable of causing said free drawing edge to assume varying degrees of circular curvature when the beam is flexed upon the application of a force applied to the center thereof, and beam deflecting means interposed between said main body member and the midpoint of said beam operative to apply a deflecting force to the beam for varying the curvature of the latter, said means being so disposed and operative relatively to the secured ends of the beam as to be capable of imparting to the free drawing edge thereof a curvature coincident with the arc of a circle, and additional means interposed between said main body member and said beam for varying the curvature of the latter in the regions thereof respectively extending between its pivoted ends and said first-mentioned means, said additional means being in the form of slidable elements, each of which bears an index for registry with calibrated position-indicating scales provided upon said body member.

12. A drafting instrument comprising a main body member, a flexible beam pivotally secured at its ends to said body member the adjacent edges of said body member and of said beam being spaced from each other, rotary means at the center of said body and other means disposed in said space on each side of said rotary means and slidable longitudinally with respect to said body and said beam, all of said means being operative to vary the position of said beam with respect to said body member, said beam being provided with a free drawing edge and being characterized in that at least one edge of the beam throughout its full length extending freely between the pivotally secured ends thereof, when in unflexed state, is of a curvature capable of causing said free drawing edge to assume varying degrees of circular curvature when the beam is flexed upon the application of an edgewise pressure applied to the center thereof and along a line extending radially of its curved edge.
